(57) **CLAIM**

The ornamental design for an electronic vaping device, as shown and described.

DESCRIPTION

FIG. 1 is a perspective view of another embodiment of a new design for an electronic vaping device.

FIG. 2 is a front view of the system of FIG. 1.

FIG. 3 is a back view of the system of FIG. 1.

FIG. 4 is a left side view of the system of FIG. 1.

FIG. 5 is a right side view of the system of FIG. 1.

FIG. 6 is a top view of the system of FIG. 1.

FIG. 7 is a bottom view of the system of FIG. 1.

FIG. 8 is a perspective view of another embodiment of a new design for an electronic vaping device.

FIG. 9 is a front view of the system of FIG. 8.

FIG. 10 is a back view of the system of FIG. 8.

FIG. 11 is a left side view of the system of FIG. 8.

FIG. 12 is a right side view of the system of FIG. 8.

FIG. 13 is a top view of the system of FIG. 8; and,

FIG. 14 is a bottom view of the system of FIG. 8.

The broken lines in the drawings depict portions of the electronic vaping device that form no part of the claimed design.
